UNITED STATES PATENT OFFICE.

NEWMAN R. MARSHMAN, OF NEW YORK, N. Y.

TYPE-WRITING MACHINE.

SPECIFICATION forming part of Letters Patent No. 636,156, dated October 31, 1899.

Application filed September 26, 1898. Serial No. 691,871. (No model.)

To all whom it may concern:

Be it known that I, NEWMAN R. MARSHMAN, a citizen of the United States, residing at New York, in the county and State of New York, have invented new and useful Improvements in Type-Writing Machines, of which the following is a specification.

By means of this invention a type-writing machine can be made of simple or cheap construction and capable of easy or rapid operation; and the invention resides in the features of construction set forth in the following specification and claims and illustrated in the annexed drawings, in which—

15 Figure 1 is a plan view of the machine. Fig. 2 is a sectional side elevation of the machine. Fig. 3 is a section along $\alpha\alpha$, Fig. 2.

The base or foot of the machine is shown at 1, and a carriage 2, carrying platen or paper roller 3, can be suitably fed as the writing progresses. A type-bar 4, Fig. 2, being driven by hammer 5 toward the platen, will, by aid of ink-ribbon 6, produce the required print. The type-bars are mounted on a carrier adapted to move or swing about shaft 7, and these bars swing back and forth or toward and from shaft 7. This carrier is shown in form of a wheel or segment, the rim portion being shown in two parts or sections 8 and 9, the spokes at 10, and the hub portion at 11. The rim being slotted, as seen at 12, the type-bars 4, swinging or moving in the slots, are properly guided or steadied by the slotted upper and lower rims 8 and 9 or guided by rim 8 and supported by rim 9. The type bars or levers 4 are shown with their arms

35 14, Fig. 2, slotted or forked to straddle or swing on the rod or fulcrum 15, carried by lower segment-section 9. The slots 12, with 40 forked arm 14, allow the type-bars to be readily removed or inserted into place. The returning-springs 79, connected or removably hitched to their respective type-bars and to upper carrier-section 8, tend to hold the bars

45 or type clear from platen 3. The type-bar may be considered as a lever of the first class, with fulcrum between the lever ends, the type end being at 4 and the lifter contacting end at 14. The bars when printing are held 50 or guided by the fork or guide 16 on post 17, located at the printing-point.

The stem or shaft 7 is shown fixed or secured to base 1, and the carrier-hub 11, sitting loosely about the stem, has a sleeve or tube 18, Fig. 2, with collar 19 resting on tube 55 or sleeve 20, so that the carrier will not sink below the required level on the rod 7. The sleeve 20 is also rotatable on this rod and can be made to rest on base 1. This sleeve 20 has a rearwardly-extending arm 21 and a forwardly-extending arm 22, which latter may be called a "locking or holding arm," since, as presently seen, it locks or holds the segment 8 while the required type-bar prints or holds the segment in position for the hammer to actuate a bar. The arm 21 has a pin 23 engaging the fork or slot 24 of arm 25, secured to the segment or hub 11. As the segment rotates the arms 21 and 22 are thus likewise rotated. The segment carries a joint or pivot 60 rod 26 for links 27, located one on each side of and a suitable distance from shaft 7. The links are jointed or connected by pivots 28 to a fork portion 29 of arm 30, having the finger-ring or eye 31. This arm 30 might be called 65 a "setting-arm," since when moved or swung by the operator it will rotate the carrier 8 to bring the required type to the printing-point. The arm 30 could be omitted and the setting of the carrier done by arm 22; but the arm 30 70 is in convenient reach or accessible to the operator.

Rising from base 1 are posts or blocks 32, Fig. 1, suitably spaced to allow the required movement to arm 22. These blocks carry 85 fulcrum or rod 33 for the key-levers 34 35, the arms 34 having finger-buttons 36.

The hammer 5 may be considered as one arm of a lever, the other arm of which is in form of a bail having arms 37 and cross-piece 90 38, the fulcrum being at 39. The ring 31 being set over a certain button 36, the carrier 8 is turned to bring the corresponding type-bar to the printing-point, and such button 36 being then depressed the corresponding key 95 is actuated, so that arm 35 swings bail 38 to cause the hammer 5 to strike the required type-bar.

On base 1 are suitably-spaced blocks or risers 41, carrying a guide 40, made in form 100 of a comb or slotted plate. The key-arms 34 when at rest lie in the respective slots in guide

40. The locking-arm 22 is shown provided at its forward part with a fork or lock piece 42, having slot 43. When the setting-arm 30 has been moved to a certain key, the arm 22 has 5 moved slot 43 to such key, so that on the latter being actuated its arm 34 clears or passes out of guide 40 and into slot 43, so as to lock arm 22, with the carrier 8, in position for the required type to print. In other words, the 10 keys or arms 34 are normally raised, so as to lie up in the slots in comb or guide 40. When, however, a button 36, with arm 34, is depressed, such arm 34 swings down away from and out of comb 40 and toward and into the fork 43 15 of arm 22. The arm 22 is thus locked against motion in either direction by a key-arm 34, entering between the tines or prongs of fork 43.

From the hammer-lever 5 37 extends an arm or tail 44, Fig. 2, engaging arm 45 of lever 45 46, fulcrumed at 47. The arm 46 engages the ribbon guide or plate 48, which is shown having a pin-and-slot connection with the fixed post 17. This guide 48, with its ribbon, is normally down to clear the view to 25 the platen; but when hammer 5 swings back to print the lever 45 46 is swung to raise the carrier 48, with the corresponding ink-ribbon portion, to the printing line or position. The arm 46 or lever 45 46 when made of springy 30 metal or material can give when required to prevent breakage. The upper part of the ribbon-guide is of course suitably slotted or shaped to allow the type-bar 4 to pass to or strike the platen 3.

35 The ink-ribbon 6 is shown in form of an endless tape and passes from the ribbon-guide 48 to the spools 49, 50, and 51. The spools 49 and 50 are shown with their spindles 52 and 53 rising from base 1. To keep 40 the ribbon taut, the spools 50 may have their spindles 53 somewhat springy and tending to pull the ribbon away from the printing-point; but of course the ribbon must not be held back so taut as to interfere with the type-bar 45 giving a proper printing stroke or driving the ribbon against platen 3. The spool 51 is shown mounted on stem 7 and is rotated to feed the ribbon. The carrier-hub 11, in addition to the downwardly-extended sleeve 18, 50 has the upwardly-extended sleeve 54, with arm 55 engaging disk 56, having pawl or spring tooth 57. The spool 51 has at its lower face a ratchet or teeth 58. The carrier, as seen, moves transversely or is rotated from 55 side to side by handle 30, and the sleeve 54, with arm 55 and pawl 56, oscillates with the carrier. As the pawl-tooth 57 swings one way it glides past the teeth 58, while its movement in the opposite direction is imparted to 60 the spool 51 and the ink-ribbon.

The type-bars 4 are normally in such position that their arms 14 lie clear of a lifter or block 59 below the printing point or guide 16. When, however, a bar is actuated by hammer 5, the arm 14 comes to rest on block 59, so as not only to firmly support or steady the

bar 4 when printing, but also to give said bar a slight lift or rising motion, whereby the type-bar is moved longitudinally or its type brought to the printing line or level even if 70 the carrier 8 should be somewhat out of level. As motion is eased by making the carrier as light as possible, the latter could not be depended on for accurate leveling or alinement of the type-bars. The tendency of the type-bars to drop or swing their arms 14 clear from block 59 will cause an easy or rapid return of the type-bar when released after having been forced by the hammer onto the lifter. In other words, the type-bars strike the lifter 80 when printing and clear the lifter when returning to rest.

The block 59 is supported by or has a seat on post 17. The type-bars can each have one or more type, as required. In the drawings 85 are shown three type on a bar, the upper type or case normally printing. To bring another case to print, the carrier 8 must be raised, and to enable the block 59 to be likewise raised to accompany the case-shift of the type-bar such block is movable vertically in its seat 60 in post 17. The case-shift can be effected by shift-keys 61 and 62, one arranged to shift to middle case and the other to lower case. These keys are shown on opposite sides 95 of the machine, but could both be located at the same side, and a description of one shift-key explains the action of the other. The shift-key is fixed to cross-arm 63 of a bail, whose arms 64 are fulcrumed at 65. One arm 64 engages under the carrier or its hub 11 and the other under block 59. As the key 61 or 62 or its button 67, with cross-piece 63, is depressed the arms 64 lift the type-bar carrier and block 59 to the required level. Guides 105 66 can be made to steady the shift-keys and also to limit the play or depression of each key, as required, to shift the corresponding case into action. The shift-bails 63 pivot at 65, and these bails have the arms 62 rigidly secured thereto, so that the arms 62 likewise pivot at 65, and the forks or split blocks 66 guide the arms 62 in their rise and fall.

The feed of carriage 2 can be effected in any suitable way, as the machine is not limited to a particular kind of feed. In the drawings the carriage is shown with a rack 68, and a pawl 69 extends from arm 70, which is mounted on rock-shaft 71, and as the latter rocks the pawl, oscillating along rack 68, will alternately glide over and take hold of the same to feed. The rock-shaft 71 has arm 72, engaged by arm 73, extending rearwardly from the hammer-lever or its arm 37. As a key 35 actuates the hammer the arms 73 and 72 turn shaft 71 to move arm 70 and pawl 69 in one direction, and a return-spring can be suitably applied to the pawl to return the latter and feed a step on the release of key 35.

The spacing arrangement for spacing between words can be of any suitable kind. An arm 74, extended from rock-shaft 71, is shown

engaged by arm 75 of space-key 75 76 with button 77 and fulcrum at 78. As the button 77 is depressed the arms 75 74 move the rock-shaft 71 the same as the dip of arms 72 and 73.

5 As each type-bar 4 swings or is fulcrumed independently of the others, the stroke of the hammer on one bar will not disturb others, the hammer or its fulcrum being located or fixed at the printing-point, so that the particular bar at such point is engaged by the hammer. The movable or link connection 27 enables the setting handle or eye 31 to swing or be moved toward or from shaft 7 or back and forth, as required, to reach a certain key 15 or button 36, these key-buttons being conveniently arranged in rows or banks. The slits 12 are practically alined with the key-arms 24, lying forward of fulcrum 33, said arms 34 and slits 12 being arranged to radiate from a common center or stem 7. By suitably bending the arms 35 back of fulcrum 33 out of line with the arms or forward portions 34 said arms 35 will clear post 7. The springy spindles 53 of spools 50 can be steadied or housed 20 in posts or tubes suitably slotted or open toward printing-point 16 to allow the ribbon to be struck or carried to the paper or platen 3. The pin 23, being of suitable length, will remain in engagement with slot 24 even when 25 the latter, with the segment, is lifted or moved away from arm 21.

What I claim as new, and desire to secure by Letters Patent, is—

1. A type-writing machine provided with a 35 type-bar pivoted between its ends, and a lifter or block below the pivot for the rise or alinement of the bar when at the printing position substantially as described.

2. A type-writing machine provided with a 40 pivoted type-bar having an arm made to extend below the pivot, and a lifter or block below the pivot, said downwardly-extending arm being made to rest on said block to raise or aline the type-bar when the latter is at the 45 printing position substantially as described.

3. A type-writing machine provided with a type-bar pivoted between its ends and having type fixed to one of its ends, and a lifter or block below the pivot, said type-bar having 50 its lower end below the pivot made to ride on or contact with the lifter substantially as described.

4. A type-writing machine provided with a type-bar, a movable carrier or segment for carrying the bar to and from printing position, and a lifter or block fixed at the printing position, said bar being made to strike the lifter when printing and to clear the lifter when returning to rest substantially as de- 55 scribed.

5. A type-writing machine provided with a type-bar, a movable carrier or segment, and a lifter or block fixed below and back of the segment at the printing-point, said bar having 60 a downwardly-extended arm projecting below the carrier to be supported on the lifter when

printing and to fall clear of the lifter when returning to rest substantially as described.

6. A type-writing machine provided with a movable segment, a type-bar on the segment, 70 a lifter or block fixed at the printing position below the segment, and a hammer having a fulcrum fixed at the printing position forward of the lifter so that the segment carries the type over the lifter and back of the hammer 75 substantially as described.

7. A type-writing machine having a base 1 provided with a post 17 fixed at the printing position and having a seat, a block 59 placed on said seat and having a guide-pin 60 extended into such post, type bars or levers, and a movable wheel or segment above the block for carrying the bars to the block, said bars being extended below the wheel toward the block to reach into contact with the latter and 85 said post 17 being extended upward above the block-seat and having a guide 16 for the upper bar portion substantially as described.

8. A type-writing machine provided with a transversely - movable segment, forwardly 90 and backwardly movable type-bars pivoted to the segment and extended below the same, type fixed to one end of the bars, a lifter or block for the bars below the segment, and means for actuating the segment and bars 95 substantially as described.

9. A type-writing machine provided with a type-bar, and a carrier or segment for carrying the bar to the printing position, said carrier having several sections for steadyng or 100 guiding the bar and means independent of the segment for leveling or alining the bar while making the printing stroke substantially as described.

10. A type-writing machine provided with a 105 type-bar, and a carrier or segment for carrying the bar to the printing position, said carrier having a section for guiding the bar and a section for supporting the bar and means independent of the segment for leveling or 110 alining the bar while making the printing stroke substantially as described.

11. A type-writing machine provided with a type-bar, and a carrier or segment for carrying the bar to the printing position, said carrier having an upper section for guiding the bar and a lower section provided with a fulcrum or rod for such bar and means independent of the segment for leveling or alining the bar while making the printing stroke substan- 115 tially as described.

12. A type-writing machine provided with a type-bar, and a carrier or segment for carrying the bar to the printing position, said carrier having a section for guiding the bar and 120 a section provided with a fulcrum or rod for such bar, and said bar having an arm forked or open to straddle the fulcrum substantially as described.

13. A type-writing machine provided with a 130 type-bar, and a carrier or segment for carrying the bar to the printing position, said car-

rier having sections open or slotted for allowing the type-bar to be mounted and removed, and for engaging or steadyng the bar when printing and when at rest and one of the sections having a fulcrum for the bar substantially as described.

14. A movable segment or carrier having an upper and a lower section, type-bars fulcrumed to the lower section, and a returning-spring for each bar, said springs being each connected independently of the others to the upper segment-section and to its respective bar above the upper section to be at a distance from the fulcrum substantially as described.

15. A type-writing machine provided with a carrier or segment, type-bars on the segment and extended below the latter, a lifter or block below the segment, and a shifter for the segment and lifter substantially as described.

16. A type-writing machine provided with a carrier or segment, type-bars on the segment, a lifter or block separate from the segment, and a shifting-bail having its arms made to respectively engage the segment and lifter substantially as described.

17. A type-writing machine provided with a type-bar having a plurality of type or case, a bar carrier or segment made movable transversely or across the machine and vertically shiftable, and a vertically-shiftable lifter or block fixed at the printing position so as to engage the type-bar when the latter is brought to such position substantially as described.

18. A type-writing machine provided with a carrier or segment, a type-bar on the segment, a lifter or block for the bar, and a shifter for the segment and lifter substantially as described.

19. A type-writing machine provided with a shiftable carrier or segment, a type-bar on the segment, a shiftable lifter or block for the bar, and a shifter made to engage or simultaneously shift the segment and lifter substantially as described.

20. A type-writing machine provided with a series of independently fulcrumed or swinging type-bars, a lifter or block below the type-bars at the printing position of the latter and a hammer in front of the lifter for giving a bar a printing stroke said bars being movably mounted so as to be carried to the lifter back of the hammer substantially as described.

21. A segment or carrier, type-bars on the carrier, a carrying-arm for moving the carrier to bring the bars to printing position, a hammer at such printing position, and keys for actuating the hammer, such keys being separate from the carrying-arm so that the actuation of a key will not set or move the carrying-arm substantially as described.

22. A segment or carrier, type-bars on the carrier, a carrying-arm for the segment, a hammer, and keys or key-levers for actuating the hammer, said carrying-arm being made movable independently of said keys and said

keys being clear of or permanently out of engagement with the carrying-arm so that the actuation of the keys will not move the arm substantially as described.

23. A segment or carrier, type-bars on the carrier, a carrying-arm for the segment, a hammer, key-levers for actuating the hammer, and a fulcrum for the levers, said segment being slotted to receive the bars, and said key-levers having the portions forward of the fulcrum alined with the segment-slits substantially as described.

24. A segment or carrier, type-bars on the carrier, a carrying-arm for the segment, a hammer, key-levers for actuating the hammer, and a fulcrum for the levers, said segment being slotted to receive the bars, and said key-levers having their forward arms alined with the segment-slits and the rear arms bent out of line with the forward arms substantially as described.

25. A type-writing machine provided with type-bars, a segment or carrier for movably supporting the bars to successively carry the latter to the printing position, a hammer having its fulcrum fixed at the printing position, an actuating-bail for the hammer, keys for the bail, and a carrying-arm or setter for the segment said keys and setter being made movable independently of one another substantially as described.

26. A type-bar, a segment or carrier for the bar, a setting-arm for the carrier and bar, keys beneath the setting-arm and a locking-arm for the segment separate from and located beneath the keys and the setting-arm substantially as described.

27. A type-bar, a segment or carrier for the bar, a hammer, a setter for the carrier and a holder or locking-arm for holding the segment in position for the hammer to actuate the bar said setter and holder being separate from or made to act independently of one another and said holder being located beneath the setter substantially as described.

28. A type-bar, a segment or carrier for the bar, a hammer, a holder or locking-arm for holding the segment in position for the hammer to actuate the bar, a fork on the holder, and keys for actuating the hammer and for engaging the fork to lock the holder and carrier said holder being separate from or actuated independently of the keys substantially as described.

29. A type-bar, a segment or carrier for the bar, a hammer, a holder or locking-arm for the segment, a fork on the holder, hammer-actuating keys, and a setting-arm for the segment, said setting-arm being independent or separate from the keys and having a finger-ring made to be moved to or over a desired key substantially as described.

30. A type-writing machine provided with keys, a type carrier or segment, a shaft about which the carrier rotates, a carrying-arm forked about the shaft, and links jointed to

the segment and forked arm to allow the latter to move back and forth to various keys substantially as described.

31. A type-writing machine provided with a key, a guide or comb for the key, a type carrier or segment, a holding-arm for the segment, and a fork on the arm, said key being made to oscillate between the comb and the fork, and said holding-arm being made mov-

able independently of the key substantially to as described.

In testimony whereof I have hereunto set my hand in the presence of two subscribing witnesses.

NEWMAN R. MARSHMAN.
